METHOD OF PRODUCING PICTURES BY
DISCHARGE

Francisco G. Yanes, New York, N. Y., assignor,
by direct and mesne assignments, of thirty
per cent to Tomas Pacanins, New York, N. Y.,
and fifteen per cent to Florencio Gomez,
Trujillo City, Dominican Republic

Application July 15, 1937, Serial No. 153,696

7 Claims. (Cl. 101—149)

The invention specially relates to photographic color reproduction by means of two-element analysis and a synthesis involving only two images which are produced in combination with a special 5 material where color-providing substances are proportionately prearranged. Although intended for two-color separation, the material may obviously supply part images for other color synthesis.

10 The polychromatic pad may be described as a dry material comprising a support coated with a medium non-sensitive to light in which a plurality of color-providing substances are proportionately incorporated and prearranged for chromatic effects. Such pad may be used as a dyeing element or as a color picture foundation. It is as a picture foundation that the pad will be here considered.

In the drawing:

20 Fig. 1 illustrates a bi-color pad.
Fig. 2 is the four color tonochromatic form of the pad.

Fig. 3 shows a three color type.

25 Fig. 4 presents the pad as a potential dyeing element.

It is well known that in processes of the imbibition group it is necessary to prepare and keep in working condition dye solutions for impregnating the matrices, and also that for color work those 30 solutions must be exactly mixed and preserved in order to maintain their relative degree of concentration, complementary quality and other characteristics. To this it may be added that every color needs an individual outfit for using, 35 washing and storing which, even for the small shop, is cumbersome. To overcome those difficulties I conceived as an article of manufacture a dyeing element carrying selected and proportionate color-providing matter and which could 40 be produced in standardized type and stored in dry condition until the moment of using it; in other words, a material which, after wetted, would provide a sort of a pad in which to "ink" the "rubber stamp," as the matrix was called in 45 early descriptions of the imbibition processes.

Although the opportunity of finding a manner for choosing, proportioning and maintaining the standard of the coloring together with the simplification of dyeing outfit was enough to justify 50 the chromatic pad, that idea was only the point of departure for developing my invention into a dyeing element susceptible of supplying more than one color under controllable conditions. I found that migrating colors held in superposed 55 layers, provided there were not a great difference

in their respective rate of penetration, behave as a single color and transferred in order, to the point of making feasible to give a different coloring to the light and heavy tones of an absorbent image respectively. This new achievement 5 offered a method of double-coloring of the images for the synthesis in two element processes when the negatives of the separation respectively record a group of complementary colors.

Yet, while investigating the possibility of introducing an element of certainty in the application of double-coloring to photographic images, I still developed my invention to a point that the chromatic distribution was more precise and the general quality of the color images improved upon 15 the lack of definition usually shown by multicolor dye-prints. I found that a potential polychromatic arrangement was dischargeable by negative absorbent images, and that the remaining colors formed a clean and sharp positive chromo- 20 type.

It is a known fact that the imbibition and like processes have been the subject of innumerable improvements regarding the lack of sharpness and registration of the images. On one side retarders, accelerators, cleaners, and other assistants have been proposed to be added to the dye baths, in such a matter of fact manner that a patent was granted for not making use of any. On the other hand, the support or blank where 30 the dye image is transferred has also become a subject of attention, and hardeners, mordants, reagents, toppers and other fixers have been recommended. But the situation has necessarily remained in a sort of compromise because the 35 very diffusion of the dyes and the expansion of the support which are intended to be reduced are the cause of the migration and suction utilized in those processes. A sort of drawback inherent to the method of working which, in color photography, is multiplied on account of the number of 40 images which must be combined.

However, when I use the pad of my invention as a foundation to obtain pictures by discharge and sandwich the wet material between two 45 photographic negative reliefs of gelatine in register, the migration of the dye is limited in space because the discharging element is formed by absorbent sections of definite volume, contrary to the case of a blank offering the colors both the 50 whole surface and depth of a gelatine layer. Under the new technique which seems to be the proper one, the only possible diffusion would be sideways from the colors remaining in the film towards the space left by the migrating ones. 55

But as long as the suction takes place along a line perpendicular to the film and not only two but three and even four colors may be simultaneously discharged, the limitation of time also contributes to minimize any possible lack of sharpness. 5 Four colors carried away in the time necessary for discharging one and a quick drying of the film present a great improvement over the regular imbibition work. Another point is that the 10 film can be made practically diffusion-proof by coating the support with a substratum carrying a colorless migrating substance which as the transferring goes on fills the sections left by the colors in the deepest layers. The tonochromatic pad 15 illustrated in Fig. 2 is an example which satisfies both the chromatic and the photographic quality of the reproduction.

A very simple form of a bi-color pad is illustrated in Fig. 1. It comprises a support S carrying two coatings of a medium in which two migrating color-causing substances are incorporated. I may produce this dyeing element in a support of Celluloid and use as a medium gelatine which is previously dyed to the desired shade 25 and applied at ordinary emulsion coating temperature of 33° to 35° centigrade. For purposes later described hard gelatine is preferable and should the saturation of the color be too great it may be cut by adding more gelatine. The temperature should never be raised further than necessary for mixing or coating as it may affect some dyes. I usually add small amounts of glycerine to prevent the brittleness of the coating. Instead of Celluloid the support may be 30 made of collodion, and many other suitable materials including a self supporting medium; and regarding the medium other colloids or matter fulfilling the purpose may be used. The color-causing substances are also many and may be 35 incorporated in the medium in different manners. However, I prefer the described example, as liable to permit a controlled and standardized production in a commercial scale.

The practical advantage of the "inking" pad 45 presented in Fig. 1, may be fully realized by considering that it is not a mere color dispenser, for complementary colors of the required shade may be chosen, proportioned and prearranged to permit the correct and simultaneous dyeing of two 50 matrices. I do that by sandwiching between them, at moderate pressure, the color-supplying element previously soaked in water in the presence of an assistant which prevents the bleeding of the colors, as for instance, a slight amount 55 of a weak acid for certain groups of dyestuffs. The wetting of the pad may obviously be performed by any suitable means preventing the bleeding of the colors, as by a sprayer or even by the image to be colored itself in certain 60 processes. I have even found that when the amount of glycerine that I usually add to the pad to prevent brittleness is excessive, the damp condition caused by the atmosphere is sufficient to produce a transferring from a practically dry 65 pad especially towards mordanted images. A further advantage of the dyeing element is that the colors can be proportionate for the heavy tones, and once the equilibrium of imbibition is realized for the lighter tones, the heavy ones cannot take 70 more color than is present in the section they contact, so it is possible to control the contrast. Of course the proportionate color-causing-matter in the double element in Fig. 1 can be produced in two separate supports which for mere dyeing 75 purposes need not be made of a transparent sub-

stance and in such form they also may be used for final coloring of a transparency whose complementary values are produced on opposite sides of a double coated film carrying two absorbent images. A separate, one-image-dyeing-element, 5 is illustrated in Fig. 4 for double-coloring.

The simultaneous "inking" of the two matrices by means of the element shown in Fig. 1, leaves this, after used, without any further application. However, this waste is avoided when the material 10 is used as a foundation for the picture. I may produce through the photographic process instead of positive reliefs reversed or negative absorbent images which when dyed by the element 15 will leave in this the positive color picture. And 15 as long as said negative matrices can be washed and used again many copies can be reproduced. So the dyeing element has both the advantages of a controllable dyeing device and a sort of chromatic foundation for the production of a 20 picture. This color foundation, as explained, is susceptible of being manufactured to fit negatives of different contrast.

When the element illustrated in Fig. 1, is used as a foundation where colored pictures are produced by discharge, I may add a feature shown in Y which separates the support from the orange layer 2 and the blue-green layer 3. The same feature is shown in Figs. 2, 3 and 4. That sort of substratum which is not indispensable when 30 the layers are thin and hardened, is a precaution to prevent any side invasion of coloring matter and preserves the sharpness of the picture. It merely consists of a hardened colorless substratum carrying a dye repellent colorless salt which 35 as the migration takes place seems to move in the line of absorption. Although the function of this substratum is rather physical, many dyeing assistants well known in the industry can be used in a small proportion according to the class 40 of dyestuff. Another precaution when using the element as picture foundation is to add to the soaking solution a hardening substance as 1 to 2% of formaldehyde for instance. After the discharge takes place the film must be quickly dried. 45 As it is, the material in Fig. 1 might be used in cinematography for two-color pictures and even the amateur will be offered the easiest and most economic way of producing a color photograph. A thin sheet of the double coated material formed 50 on a thin and flexible support may be soaked and sandwiched between the two negatives in register of a bi-pack transformed in absorbent dye-discharging images.

I shall here summarize the main points of the 55 potential polychromatic prearrangement duplicated in Fig. 2. One side of the transparent support S carries a thin yellow coating 7 and a magenta thicker layer 5; this pair transmit a strong red, but if color is discharged in depth 60 lighter reds, oranges and yellows may be produced showing a pigmentary imitation of one end of the spectrum. The pair blue-violet 6 and green 8 on the other side if subjected to similar discharges will reproduce another complementary section of 65 the spectrum. It can be easily understood that a negative photographic relief of gelatine, having a varied absorbing capacity according to the tones, will make proportional discharges on each 70 side. And as the two-element analysis according to the tonochromatic system have been arranged to separate the two scales of colors and adjusted to record them in the same spectral order adopted in the material, a full color picture will be obtained. 75

Instead of having four strata, the pad may be built as in Fig. 3, where a single blue-green stratum 11 is opposite to the pair magenta-yellow 10—12. Or as in Fig. 1, where both pairs are represented by intermediate colors as the red-orange 2 and blue-green 3.

The method of producing a picture by discharging colors from a polychromatic pad is not a mere reversed imbibition. The results obtained 10 are new. In the first place the colors can be arranged in their proper position and given the exact saturation and quality, something hardly possible by letting them freely migrate; and the better result is secured precisely because the 15 picture is not formed by the migrating colors but by the ones remaining in the film, and these have been selected, proportioned and prearranged. In the second place the migration is limited by the discharging element which, in combination with 20 the factor time in the simultaneous discharge, and other precautions, assures a superior sharpness. On the other hand, the simultaneous migration of two colors unmixed and in order is not a step in the old process where the application 25 of double-coloring usually comes after many complications of uncertain results. The method of polychromatic discharge of my invention which by no means is limited to migrating dyes and absorbent images, is to imbibition what 30 bleaching is to coloring, an entirely different process.

The method of polychromatic discharge accessory to the polychromatic pad may be performed in different manners although in the same substantial way. The color-migration has been adopted as example because it permits an easier demonstration; the thickness of the layers, for instance, is a materialization to show proportion, but that proportion could be realized in other 40 ways. Then the discharge does not necessarily need to be produced by absorbent images, for other reactions of chemical nature may produce the same result. Or both the physical and chemical phenomena may be combined. For instance 45 using a mordanted image or a combined relief and mordanted discharging image. Another point is that the migration is not an exclusive property of certain dyestuffs, for many substances susceptible of color reaction may be subjected to discharge for a later chromatic development, as for instance, metallic salts, which can be transformed into color precipitates with 50 different reagents. The only question is that in the discharging process of my invention, those 55 color-providing substances, whether actual or potential, are not offered a surface and a depth where to freely diffuse; they find a limited field; and regarding the material where they remain they are where they belong.

60 I wish to be understood that although some parts of my invention may be practiced in many forms and by using many substances and reagents, it will be within its scope a system which would combine a chromatic prearrangement in 65 a material non-sensitive to light and a method of polychromatic discharge, whether said prearrangement is produced or prepared by actual dyestuffs or substances giving color reactions and whether said discharge is caused physically or chemically in combination with a photographic image.

I also wish to be understood that the potential tonochromatic prearrangement shown in Fig. 2 as a non-sensitive type of the tonochromatic film 75 fully described in the already mentioned coap-

plication, is an independent invention regardless of the method of processing it or whether the color-providing substances are dischargeable or developable even by an ordinary imbibition process.

I claim:

1. A method of color photography which consists in first procuring a material having a transparent support, a medium non-sensitive to light coated on both sides of said support, said medium carrying in dry state at least one pigment on each side, the transmission of said pigments respectively corresponding to colors preferably complementary, so as to transmit in combination a substantially neutral color, said pigments so chosen that by not having much affinity for said medium are easily discharged when said medium is contacted in suitable conditions by a medium possessing a stronger affinity for said pigments; second, producing a photographic color separation in two images of negative character on two separate films, said images in reversed position in regard to each other so as to come into register when the emulsion side of both films are in contact, the color values of said images respectively corresponding to the colors transmitted by each side of the material described in the first step; third, processing said images of negative character by well known means as to create in said images a strong affinity for the pigments present in the material of the first step; fourth, softening the material of the first step in a suitable manner preventing the bleeding of the pigments; fifth, sandwiching the softened material between the processed negatives of the second and third steps, after bringing them in register, so that the greater affinity of the images for the pigments will discharge the negative complementary values from the film, said discharge being assisted by a suitable pressure maintaining the contact in the sandwich; sixth, allowing the necessary time to obtain said discharge; and seventh, extracting the final picture from the sandwich and drying it rapidly.

2. A method of color photography which consists in procuring a material having a transparent support, a permeable medium non-sensitive to light forming a plurality of strata distributed on both sides of said support, each of said strata carrying a different pigment, one of the sides of the support at least having two strata, these two strata so arranged in relative thickness, and their corresponding pigments so selected in regard to hue and saturation, that said two strata will transmit in combination by successive discharges in depth of color matter a succession of colors corresponding to one end of the spectrum; the pigments in the opposite sides of the film so balanced that one side will transmit a color preferably complementary to the color transmitted by the other side; said pigments so chosen that by having little affinity for the medium forming the different strata will be easily discharged when said medium is contacted in suitable conditions by a medium possessing a stronger affinity for said pigments; producing two elements bearing complementary negative images in reversed position, one of said images at least representing a scale of colors corresponding to one end of the spectrum, said images so processed as to cause by contact with the material of the first step the discharge of said pigments; sandwiching said material in wet condition between the two negative discharging images in register; allowing time for such discharge with

the assistance of a suitable pressure; and separating and drying the final picture.

3. A method of color photography which consists in procuring a material having a transparent support, a medium not sensitive to light coated on both sides of said support, said medium forming two coatings of different thickness on each side of said support, said medium carrying dischargeable color providing substances different for each one of said coatings, the colors corresponding to said coatings so chosen that each side respectively will reproduce by successive discharges in depth of color causing matter a scale of colors respectively corresponding to a different end of the spectrum; wetting said material in such a manner as to prevent the bleeding of said color-providing substances; and sandwiching said material between two negative elements in register, said elements bearing images so processed as to discharge by contact the coloring matter, said negative images substantially representing complementary values obtained by a method of analysis in which the colors represented by each element rank in the same spectral order than the color scales potentially prearranged on each side of the material.

4. A method of color photography which consists in procuring a material including a transparent support coated on both sides with a substantially plain colloid, said colloid carrying in a dry state a plurality of migrating dyestuffs; soaking said material in a water solution containing an assistant to prevent the bleeding of the colors; and sandwiching the wet material between two absorbent negative reliefs of gelatine in register until the discharge of the negative values is produced, the color values of said absorbent negative reliefs respectively corresponding to colors complementary to the pigments present on each side of the material.

5. In a process of the character described the step of producing a part image showing a graded scale of colors which consists in procuring a material including a support and two superposed coatings of a medium on said support, one of said

coatings carrying a migrating pigment representing a pure spectral color and the other coating carrying a second migrating pigment which when mixed with the first pigment in different proportions will produce the other colors belonging to one end of the spectrum; and then contacting in suitable conditions said material with a photographic part record in which an affinity for said pigments has been created by well known means.

6. In a process of the character described the step of simultaneously producing two part images in register representing different color values and showing different coloring, which consists in procuring a material having on opposite sides of a support a pair of superposed coatings of a medium, each of said four coatings carrying a different color providing substance, so that each side provides two colors, and then sandwiching said material between two registered photographic records in which an affinity for said pigments has been created by known treatments.

7. The method of producing a picture which consists in first procuring an element including a support carrying permeable matter insensitive to light, said permeable matter holding at least a pigment so chosen that by not having much affinity for said matter can be easily discharged when said matter is contacted in suitable conditions by a second matter having a greater affinity for the pigment; second, producing a photographic record of the subject to be reproduced, the image in said record of negative character when producing a positive picture; third, processing by well known means said photographic record so that the image in said record will cause by contact with the element of the first step the discharge of the pigment from said element; fourth, producing that contact under suitable conditions of dampness and pressure; fifth, allowing time for the discharge; sixth, separating the element of the first step where the picture will appear reproduced; and seventh, preventing the diffusion of the pigment remaining in said element by known means.

F. G. YANES. 45
